UNITED STATES PATENT OFFICE.

WALTER H. SAWYER, OF PHILADELPHIA, AND ANDREW C. BOYD, OF LANSDOWNE, PENNSYLVANIA.

CHECK HOLDER AND NOTCHER.

1,395,736.

Specification of Letters Patent. Patented Nov. 1, 1921.

Application filed February 17, 1921. Serial No. 445,802.

To all whom it may concern:

Be it known that we, WALTER H. SAWYER and ANDREW C. BOYD, citizens of the United States, residing, respectively, in the city of Philadelphia, county of Philadelphia, and Lansdowne, county of Delaware, State of Pennsylvania, have invented certain new and useful Improvements in Check Holders and Notchers, of which the following is a specification.

Our invention relates to a holder and notcher for checks, such as sales checks, employed in restaurants and the like, having printed, or otherwise marked thereon, data as to costs, prices, etc., the structure being provided with means for notching a check for indicating the amount to be paid, etc.

Our holder and notcher comprises a metallic member provided with means for holding a pad or stack of checks, and provided further also with notching structure comprising a notching tooth or point spaced from which is a tongue or platen extending toward the notching tooth or point.

Our invention resides in structure of the character hereinafter described and claimed.

For an illustration of one of the various forms our invention may take, reference is to be had to the accompanying drawing, in which:

Figure 1 is a perspective view of our holder and notcher.

Fig. 2 is a central longitudinal sectional view of the same.

Fig. 3 is a perspective view of a pad of checks.

Fig. 4 is a perspective view of the holder and notcher, with fastening means therefor, with a check shown in position for notching.

Fig. 5 is a perspective view of the return bend.

Referring to the drawing, integral with the check backing or supporting plate 1 of metal is the upstanding end wall 2 integral with whose edge is the forwardly extending member 3 having the return bend 4. The plate 1, opposite the members 3 and 4, is preferably, but not necessarily, roughened, as indicated at 5, to frictionally engage the stub end 6 of a pad of checks 7, the member 3 overlying the check stubs and the member 4 adapted to press upon the check stubs or to engage the stub binder member 8, which may be a metal wire, staple or the like. Engaging in the

end wall 2 is the swivel link 9, through which may be passed a key ring 10 or equivalent, by which the holder and the checks may be hung upon the hook member 11 integral with which is the hook 12, which may be passed over a belt or other member carried or worn by the operator.

In the plate 1, preferably adjacent its end opposite the check stubs or wall 2, is formed, by stamping or otherwise, an opening 18 of any suitable size or configuration. Integral with the plate 1 is the notching point or tooth 14, projecting part way across the opening 18 toward the platen or tongue 15, also integral with the plate 1, and pointing toward the notching member.

Preferably, though not necessarily, the tooth or point 14 lies in the plane of the plate 1, while the side and end margins of the opening 18 are bent out of the plane of the plate 1, as indicated in Figs. 1 and 2, whereby a check 7, Fig. 4, may be passed over the tongue or platen 15 and under the notching tooth of point 14, in which position the check is notched by pulling it across the member 14, which notches from the edge thereof a piece, leaving a notch indicative of the amount of purchase, or affording other data or information.

As indicated in Fig. 5, the check pad engaging end of the return bend 4 may be toothed or serrated for more firmly gripping and holding the pad.

What we claim is:

1. A check notcher comprising a check supporting plate having an opening formed therein, and a notching member integral and substantially rigid with said plate, said notching member extending partially across and terminating materially short of the opposite side of said opening and having its sides materially spaced from the sides of said opening, whereby a check may be passed over said opening and under said notching member and notched thereby by movement with respect thereto.

2. A check notcher comprising a check supporting plate having an opening formed therein, a notching member integral with said plate and extending partially across said opening, and a tongue integral with said plate extending partially across said opening toward said notching member.

3. A check notcher comprising a check supporting plate having an opening formed therein, a notching member integral with

said plate and extending partially across said opening, and a tongue integral with said plate extending partially across said opening toward said notching member, said tongue and notching member being disposed in different planes, whereby a check may be passed over said tongue and under said notching member.

4. A check notcher comprising a check supporting plate having an opening formed therein, a notching member integral with said plate in the plane of said plate and extending partially across said opening, and a tongue integral with said plate extending partially across said opening toward said notching member, said tongue and notching member being disposed in different planes, whereby a check may be passed over said tongue and under said notching member.
5. A check holder and notcher comprising a plate having adjacent one end thereof a holder structure, and adjacent the opposite end thereof an opening, a notching member integral with said plate extending partially across said opening, and a tongue integral with said plate extending partially across said opening toward said notching member.
6. A check holder and notcher comprising a plate having adjacent one end thereof a holder structure, and adjacent the opposite end thereof an opening, a notching member integral with said plate extending partially across said opening toward said other end of said plate, and a tongue integral with said plate extending backwardly partially across said opening toward said notching member.
7. A check holder and notcher comprising a plate having adjacent one end thereof a holder structure, and adjacent the opposite end thereof an opening, a notching member integral with said plate extending partially across said opening toward said other end of said plate, and a tongue integral with said plate extending backwardly partially across said opening toward said notching member, said notching member and tongue being disposed in different planes.

In testimony whereof we have hereunto affixed our signatures this 14th day of February, 1921.

WALTER H. SAWYER.
ANDREW C. BOYD.
